UNITED STATES PATENT OFFICE.

HENRY KLEIBER AND FRED MEHR, OF TEANECK, NEW JERSEY.

WINDING DEVICE FOR STATORS AND ARMATURES OF MOTORS.

Application filed November 18, 1920. Serial No. 425,023.

To all whom it may concern:

Be it known that we, HENRY KLEIBER and FRED MEHR, citizens of the United States of America, residing at Teaneck, in the county of Bergen and State of New Jersey, have invented new and useful Improvements in Winding Devices for Stators and Armatures of Motors, of which the following is a specification.

- 10 The object of the invention is to provide simple and relatively inexpensive and efficient means for facilitating the winding or application of coils to the stators of alternating current motors, the armatures of direct current motors either in repair or shop work or otherwise and in analogous operations requiring the accurate positioning of winding or coils with reference to either rings or cones; and with this object in view the invention consists in a construction and combination of parts of which preferred embodiments are illustrated in the accompanying drawings, wherein:—

25 Figure 1 is a side view of an apparatus embodying the invention showing the same applied to the coil or winding of a stator.

Figure 2 is a front view of the same.

Figure 3 is a sectional view on the plane indicated by the line 3—3 of Figure 1.

30 Figure 4 is a sectional view of the foot forming the fibre holder.

Figures 5 and 6 are views of a slightly modified construction of the apparatus applied respectively to the operation of winding a stator and an armature.

35 The apparatus consists essentially of a bearing head 10 and a foot 11 one of which carries a feed screw 12 for engagement by a feed nut 13 connected with the other, suitable means being employed in connection with the feed nut for actuating the same to cause a separation of the head and foot, or an extension of the apparatus under such conditions as to force the winding or coil 14 into the seats 15 of the stator or armature to be wound.

40 In the construction illustrated in Figures 1 to 4 inclusive the head 10 is exteriorly convexed to bear against the inner perimeter of the stator shown at 16, said head preferably having a sleeve 10^a detachably fitted upon the stem 17 forming a terminal of the feed screw and secured in place by means of a pin 18 to the end that the head may be 45 interchanged with others having a different

curvature of exterior surface to suit the diameter of the stator which is to be wound. The foot similarly is provided with a stem 11^a removably fitted in a socket 19 in a stem 20 and secured in place by a pin 21 to provide for the interchanging of the foot which consists essentially of a cross head 22 provided with a seat 23 for the reception of the fibre bar 24 for contact with the coil or winding and serving upon the extension of the apparatus or the separation of the bearing head and the foot to force the coil into the seats of the stator.

45 In the construction illustrated the feed nut 13 is provided with a toothed periphery 70 forming a bevel gear with which meshes a bevel operating gear 25 having its spindle 26 provided with a terminal crank 27 by means of which a relatively quick extension of the shank of the tool represented jointly 75 by the feed screw 12 and the tubular stem 20 may be made to bring the head and foot into operative relation respectively with the diametrically opposite portions of the inner periphery of the stator in which a winding 80 is to be seated.

50 Also carried by the spindle or shaft of the operating gear 25 is a ratchet head 28 for engagement by a pawl 29 having an actuating spring 30 and mounted upon an operating lever 31, to the end that by the oscillatory movement of the lever a slow and for example rotary movement may be communicated to the operating gear 25 and hence to the feed nut to exert the necessary pressure to force the coil into the seats of the stator. The pawl 29 is provided with a terminal pin 32 by which it may be withdrawn from engagement with the ratchet teeth when it is desired to quickly set the 95 terminal head and foot elements of the apparatus.

55 In the modified construction indicated in Figure 5 the head 33 is provided with a stem 34 swiveled as at 35 in a feed nut 36 100 which is engaged with a screw threaded portion 37 of a stem 38 which carries the foot 39, said feed nut being in the form of a sleeve and having radial arms 40 whereby through the retention of the nut the shank 105 represented jointly by the stems 34 and 38 may be extended to separate the head and foot members 33 and 39 to force the coil 41 into the seats 42 of the stator 43.

60 In the form of the invention illustrated in 110

Figure 6 which is applicable more particularly to armatures of the D. C. motors, the extensible shank is represented by the stems 44 and 45 respectively carrying a bearing head 46 and foot 47, and said shank being extensible by means of a feed nut 48 which is engaged with a threaded portion of the stem 44, a strap 49 being arranged in embracing relation with the core or armature 50 to form a bearing for the head 46.

It will be understood that in the use of either of the forms of coil setting or winding apparatus embodying the invention the forcible seating of the coil under conditions tending to insure accuracy may be effected with ample opportunity for the operator to observe the progress of the work by reason of the fact that the operating means for effecting the extension of the shank or the 20 relative separation of the foot and head elements thereof may be actuated slowly and at the same time with the minimum of effort on the part of the operator; and it will further be obvious that the seating of the 25 coil by means of a steady and slow pressure due to the relative movements of the head and foot elements of the apparatus can be accomplished with less risk of injury to the winding or the insulation thereof than is 30 possible when as in the ordinary practice the operation is accomplished by the aid of a hammer or like tool for impelling a bit or punch.

In particular let it be noted with reference 35 to the forms of apparatus illustrated in Figures 1 to 4 inclusive that having once set the head and foot elements by means of the crank 27 through the diameter of the stator, the alternate extension and contraction 40 of the shank necessary to force the coil into the seats of the ring may be effected by an oscillatory or vibratory movement of the operating lever 31, the tool being shifted

after each operation to bring the foot there- 45 of into proper relation with successive coils, so that the winding operation may be effected expeditiously as well as efficiently.

Having described the invention, what is claimed as new and useful is:—

1. A coil setting or winding apparatus 50 having an extensible shank provided with terminal head and foot elements, and means for effecting an extension and contraction of the shank, the head and foot elements being interchangeably connected with the 55 members of said shank.

2. A coil setting or winding apparatus having an extensible shank provided with terminal head and foot elements, and means for effecting an extension and contraction 60 of the shank, the foot member consisting of a curved cross head forming a fibre holder.

3. A coil setting or winding apparatus having an extensible shank provided with terminal head and foot elements, and means 65 for effecting extension and contraction of the shank, the head element having a convexed upper face for bearing engagement with the inner periphery of a stator and the foot element being provided with means for 70 engaging a coil to force the latter into the stator slots.

4. A coil setting or winding apparatus having an extensible shank provided with terminal head and foot elements, and means 75 for effecting extension and contraction of the same, in combination with a flexible member for disposition in embracing relation with an armature core, said flexible member constituting a bearing for said head 80 element.

In testimony whereof they affix their signatures.

HENRY KLEIBER. [L.S.]
FRED MEHR. [L.S.]
